(57) **CLAIM**

The ornamental design for a firearm component as shown and described.

DESCRIPTION

FIG. 1 is an isometric view of a firearm component, showing my new design;

FIG. 2 is a top view thereof;

FIG. 3 is a sectional view taken along the lines 3-3 shown in FIG. 2; and,

FIG. 4 is a sectional view taken along the lines 10-10 shown in FIG. 1.

The long-dash/short-dash broken lines in the application depict a claim boundary and form no part of the claimed design. The evenly spaced broken lines in the application depict portions of the firearm component that form no part of the claimed design.
